(57) **CLAIM**

The ornamental design for a slide for fretted instruments as shown and described.

DESCRIPTION

FIG. 1 is a perspective front view of a slide for fretted instruments;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a perspective view thereof; showing the design as used on a fretted instrument.

The drawing portions as shown in dashed lines form no part of the claimed design.
